UNITED STATES PATENT OFFICE.

ARTHUR C. WELLS, OF AMITYVILLE, NEW YORK.

ENGINE-STARTING DEVICE.

1,087,562.

Specification of Letters Patent.

Patented Feb. 17, 1914.

Application filed October 28, 1911. Serial No. 656,306.

To all whom it may concern:

Be it known that I, ARTHUR C. WELLS, of Amityville, Suffolk county, New York, have invented a new and useful Improvement in 5 Engine Starting Devices, of which the following is a full, clear, and exact description.

My invention relates to improvements in engine starting mechanism, and more especially to means for starting or cranking an 10 explosive engine when the engine is arranged on an automobile, although the device shown can be used for starting any similar engine.

In carrying my invention into practice I provide means for starting the engine shaft 15 by the operation of a lever which is within reach of the seat of the automobile. This is not new broadly, but where such levers have been used they have usually been combined with rather complicated mechanism which 20 is likely to get out of order, and furthermore they have generally been arranged so that any back-fire or reversal of the engine would seriously yank on the mechanism and on the arm of the operator.

25 The objects of my invention are first to provide a very simple and effective means for starting the engine shaft from the driver's seat, next to arrange the operative connection between the lever and the engine shaft so that the movement of the lever both 30 forward and back will impart a constant movement to the engine shaft in one direction, and finally to construct and arrange the apparatus so that in case of a back-fire, 35 there will be scarcely any shock to the driver.

Reference is to be had to the accompanying drawings forming a part of this specification, in which similar reference characters indicate corresponding parts in all the views.

40 Figure 1 is a side elevation of my improved apparatus as applied to an automobile. Fig. 2 is an end view of the same. Fig. 3 is an enlarged longitudinal section of the drum and clutch or casing connection with the engine shaft. Fig. 4 is a cross section on the line 4-4 of Fig. 3. Fig. 5 is a view similar to Fig. 4, but showing a modified form of clutch connection between the drum on the engine shaft and its inclosing casing. Fig. 45 50 55 60 65 70 75 80 85 90 95 100 105 110

Fig. 6 is a detail side elevation of the operating lever, and Fig. 7 is a diagram of the cable and connections for starting the engine shaft. In the drawing I have shown my apparatus applied to an automobile 10 which can be 55 of any approved type, and which has the customary arrangement of its engine shaft

11, this being arranged horizontally beneath the machine body. On the engine shaft is a fixed drum 12, and in this connection I wish to call attention to the fact that the drum is keyed directly to the shaft without the intervention of any clutch or other detachable mechanism, thus greatly simplifying the apparatus. The drum 12 is inclosed by a two-part casing 13 and 13^a, each part serving as a separate pulley and running loosely on the hub of the drum as shown clearly in the drawings. The faces of these pulley sections or casings are preferably grooved to receive the operating cable hereinafter referred to. Each pulley or casing 13 has a slipping or clutch connection with the drum 12, and I prefer to use the well-known ball gearing shown in Fig. 4, in which case the pulley or casing 13 has recesses 14 the outer walls of which are inclined, and in these run the balls 15, so that when the pulley or casing is turned in one direction, say in the direction of the arrow in Fig. 4, the balls will bind between the walls of the recesses 14 and the surface of the drum 12, thus turning the drum 12 and the engine shaft 11 forward; but when the engine shaft starts and its speed catches up with the speed of the casing or pulley, then the balls 15 will run loose in the wider portions of the recesses 14. Instead of this arrangement, an ordinary ratchet and pawl connection can be used as shown in Fig. 5, but this is not so desirable. As shown in the latter figure, the drum 12 has ratchet teeth 16 on its face engaging the pawl 17 on the pulley or casing 13.

The apparatus is worked from an operating lever 18 which as shown in Fig. 1 is fulcrumed near its lower end as at 19, and extends within easy reach of the seat of the automobile. The lower extremity of the lever 18 is pivotally connected with a rod 20, and this is provided with a turn-buckle 21 for adjusting its length. At its forward end the rod carries a pulley 22 over which runs the operating cable 23, which cable runs also over suitable guide pulleys 23^a at the corner of the machine, is wound several times around the pulleys or casings 13-13^a, and also extends around a pulley 24 which is pivoted on a lever 18 above the fulcrum 19. The pulley 24 is prevented from rotating by a common ratchet arrangement shown in Fig. 6, such as is used on many hand levers for analogous purposes. As shown, a slide

rod 25 on the lever 18 acts as a pawl and enters the recess 26 in the pulley 24, being normally pressed up by a spring 27, and the upper end of the rod connects with a crank 5 28 on the shaft 29 which is journaled on the lever 18, and has a handle 30 extending opposite the gripping portion of the lever. Thus by grasping the handle 30 with the lever 18, the rod 25 is held firmly in the recesses 26 of the pulley 24, thus locking the pulley.

The action of the apparatus will be best understood by reference to the diagram in Fig. 7. When the operator grasps the lever 18 and handle 30, he will push the lever backward and forward. Assuming that he pushes it forward first, this will draw back the rod 20 and pull on the pulley 22, and as the pulley 24 is locked against rotation, 15 the cable 23 will move on the pulley 13 so as to turn it in one direction, while the opposite direction will be given to the pulley 13^a, and when the lever 18 is reversed, the pulleys will also be reversed in their movement. Thus when one pulley or casing 13 is moved so as to turn the drum 12 and engine shaft 11 in the direction to start the engine, the other pulley will be turned back a similar distance, and the pulleys will alternately operate to keep up a continuous 20 movement of the engine shaft until the engine is started. If, now, there should be any back-fire, it will be noticed that the travel of the engine shaft and drum 12 will be reversed, which in turn will reverse the movement of the cable 23 on one of the pulleys 13 or 13^a, causing both pulleys to rotate in the same direction and rotate the lever pulleys 22 and 24. The pulley 24 being 25 thus turned back will bring a wall of the recess 26 against the rod or pawl 25, thereby moving the rod out of engagement with the pulley 24 and forcing the handle 30 from the hand of the operator, after which the cable will move freely on the several pulleys till the pawl or rod is again thrown down 30 preparatory to starting the engine.

It will be seen that there is no clutch connection between the engine shaft and crank shaft such as is common in apparatus of this kind, that the operative connection between the lever 18 and the engine shaft is one embodying the longitudinally movable cable and rotatable pulleys, and that the 35 whole apparatus is extremely simple so that its simplicity combined with the easy movements of the parts render it practically certain that the parts will not get out of order.

I claim:—

60 1. In an apparatus of the kind described, the combination with the engine shaft and a drum having a fixed connection therewith, of a pair of pulleys incasing the face of the

drum, a clutch connection between each pulley and the drum, whereby the alternate 65 movement of the pulleys imparts a constant movement to the drum and its shaft, an oscillating lever, a cable and pulley connection between the lever and the aforesaid drum pulleys by which the oscillation of the 70 lever imparts a constant movement to the drum, and a manually operated locking device to secure the cable connection with the lever, said locking device being arranged to release on a back fire.

75

2. In an apparatus of the kind described, the combination with the engine shaft and a drum thereon, of a pair of pulleys loose on the drum and incasing the face thereof, a similarly arranged clutch connection between both pulleys and the drum, an oscillating lever, a pulley carried by the lever on one side of its fulcrum, a second pulley carried by the lever on the opposite side of its fulcrum, a cable running over the two lever 80 pulleys and over the pulleys on the drum, and means releasable on a back fire for locking 85 one of the lever pulleys.

80

3. In an apparatus of the kind described, the combination with an engine shaft and a hand lever spaced from the shaft, of rotatable pulleys, each of said pulleys having a clutch operative on forward movement of the pulley to effect a connection with the shaft whereby the alternate forward movement of the pulleys imparts a constant movement to the shaft, means for intermittently rotating the pulleys simultaneously in opposite directions, said means comprising an endless cable, the same endless cable, 90 adapted to operate over the said pulleys, the said cable having a connection with the hand lever at points above and below its fulcrum, and a manually closed locking device connecting the cable with the lever, and means 95 for arranging said locking device to release 100 on a back-fire.

95

4. In an apparatus of the kind described, the combination with the engine shaft and a drum thereon, of a pair of pulleys loose 110 on the drum and incasing the face thereof, a similarly arranged clutch connection between the pulleys and the drum, an oscillating lever, a pulley carried by the lever on one side of its fulcrum, a second pulley carried by the lever on the opposite side of its fulcrum, a cable running over the two lever 115 pulleys and over the pulleys on the drum, and a manually closed latch on the lever normally locking one of the lever pulleys 120 and released by the reversal of the movement of the cable.
